SAW MILL HEAD BLOCK.

No. 295,572.

Patented Mar. 25, 1884.

UNITED STATES PATENT OFFICE.

VAN BUREN MARTIN AND CHARLES W. METCALFE, OF HOPKINSVILLE, KY.,
SAID MARTIN ASSIGNOR TO W. J. GRAHAM, OF SAME PLACE.

SAW-MILL HEAD-BLOCK.

SPECIFICATION forming part of Letters Patent No. 295,572, dated March 25, 1884.

Application filed January 24, 1884. (No model.)

To all whom it may concern:

Be it known that we, VAN BUREN MARTIN and CHARLES W. METCALFE, citizens of the United States, residing at Hopkinsville, in the 5 county of Christian and State of Kentucky, have invented a new and useful Improvement in Saw-Mills, of which the following is a specification, reference being had to the accompanying drawings.

Figure 1 is a plan view of a saw-mill carriage and track embodying our improvements. Fig. 2 is a partial vertical sectional view. Fig. 3 is also a vertical sectional view. Fig. 4 is a perspective detail view of one of the head-blocks, its rack and guide; and Fig. 5 is a perspective detail view of the graduated rule and the adjustable knee-set.

This invention has relation to saw-mill carriages; and it consists in the construction and 20 novel arrangement of parts, as will be herein-after fully described, and particularly pointed out in the claims appended.

Referring to the accompanying drawings by reference-letters, *a* designates the carriage-track, the cross-rails *b* and *b'* of which are provided, near the track-sill *c*, with guide-blocks *d* *d'*, in which a rack-bar, *e*, works longitudinally of the track. The underface of the rack-bar *e* is provided with a short rack *e'*, which 25 engages a pinion, *e''*, on a shaft, *e''*, having bearings on the under face of the track-sill *c*. The outer end of the shaft *e''* is made rectangular, and on it is slipped the sleeve *d''* of the hand-lever *d'*, which is employed to set the head-blocks forward when the log has been moved 30 over the lever *d'*.

The saw-mill carriage *f* is mounted on wheels *f'*, and is operated forward and back on its track in any of the well-known ways. A longitudinal shaft, *f''*, provided with a miter-gear, *f'''*, works in bearings *f''* *f''*, projecting from the side rail, *f'*, of the carriage-frame. The head-block guides *g* *g'* are secured to the top of the carriage-frame *f*, near its ends, and 45 project at each side, as shown, and their base portions at one end form the upper halves of the bearings *g''* *g'''*. The shaft *f''* is provided near each end with a pinion, *n* *n'*, which works in the head-block guides *g* *g'*, and engages the 50 rack-arms *i* *i'* of the head-blocks *g* *g'*. A cross-

shaft, *k*, having bearings in boxes on the side rails of the carriage-frame, is provided with a miter-gear, *l*, at one end, which engages the miter-gear *f'''*, and operates to set the head-blocks in their starting positions. An arm, *l'*, 55 prevents the miter-gears *f'''* and *l* from becoming disengaged. Near the front end of the cross-shaft *k*, and within the carriage-frame, is provided a ratchet-wheel, *l''*, which is fixed to said shaft *k*, and rotates with it when the shaft 60 is operated. The toothed portion of this ratchet-wheel *l''* is held between face-plates *l''* *l''*, which project to form guide-flanges at its ends to hold the pivoted pawls *m* and *m'* in place when in their normal positions. These face-plates 65 *l''* *l''* are provided with a loop-arm, *l''*, at one side, and have a rocking motion on the shaft *k* when operated. This loop-arm *l''* carries a triple pawl, *m*, curved, as shown, and provided with projecting arms *n'* at its lower end. 70 The loop-arm *l''* is provided with a downwardly-projecting arm, *n''*, to which the pawl *o*, for operating the loop-arm *l''*, triple pawl *m*, and ratchet-wheel *l''*, is connected, to operate the head-blocks forward, as herein-after described. 75 A detent, *o'*, is pivoted to the carriage-frame, to engage the ratchet-wheel *l''* on the side opposite the triple pawl, to prevent backward movement of the ratchet-wheel when in engagement therewith. 80

A double-crank shaft, *p*, having its crank-arms on opposite ends of its horizontal portion arranged at angles of about fifteen degrees on the same side of a vertical diameter, but on opposite sides of the axial line of a circle, has its bearing *p'* on the side rail of the carriage-frame near the triple pawl *m*, and has a central vertical arm, *p''*, connected by a loop-connection, *p''*, to the rear end of an angular rod, *q*, which passes through a guide, *q'*, its bent end 85 passing under the hinged detent *m'*, to raise it and throw it out of engagement with the ratchet-wheel *l''*, when desired. The double-crank shaft is used for this purpose, and the inner end of this double crank strikes the 90 projections on the triple pawl *m* at the same time and throws the triple pawl also out of engagement, allowing the ratchet-wheel to be turned backward with its cross-shaft *k*. 95

A curved set-rack, *r*, having teeth on the 100

outer edge, is secured to the rear face of the cross-rail r' of the carriage-frame, and curves up around the shaft k near the rear face of the ratchet-wheel l' . This curved rack r is provided with a scale by which the set of the head-blocks is adjusted. A lever, s , having a spring-pawl, s' , is secured loosely to the cross-shaft k , and said spring-pawl s' engages the curved set-rack r when in its normal position. The front end of the cross-shaft k is made rectangular in form, to receive the head of a ratchet-lever, u , which is employed to run the head-blocks back to their starting positions when a new log is to be placed on the carriage. An adjustable rule, t , graduated to inches and fractions thereof, is secured to the saw-cab in plain view of the sawyer, and is provided with a sliding knee, t' , with a set-screw or other suitable means for setting it to cut a board of the proper thickness from the log. The face of the log should be moved up against the knee-set when the first thickness is to be cut, and the knee-set then moved away from it the distance equal to the distance required for the first thickness. The set-pawl o will, when the carriage starts forward, be in the full-line position marked 4 in Fig. 2, and as the carriage moves forward its point will engage one of the teeth v of the rack-bar, and will rise into the position marked 5 in dotted lines, Fig. 2, at the same time operating the ratchet-wheel l' , and carrying the head-blocks forward against the knee set a distance equal to the distance to which the pawl o , moved by the spring-pawl lever engaging the curved rack, has been set, which is indicated on the graduated rule. As the carriage moves farther forward, the pawl o will assume the position marked 6 in Fig. 2, and will slide along the rack-bar without operating the ratchet-wheel, and when it reaches the dust-pit and slips from the rack-bar it will assume the position marked 7 in dotted lines in Fig. 2. When the frame is gigged back, the pawl o will strike the end of the rack-bar, and will assume the original position marked 4, and slide back along the rack-bar without operating the ratchet-wheel. It will thus be seen that the head-blocks will be operated forward automatically without the use of levers or screws when the log has been sawed up. The head-blocks may be run back to the starting-point by throwing the triple pawl m and the hinged detent out of gear, and lifting upon the ratchet-lever at the end of the cross-bar k and working it back and forth. By this construction we can automatically set the log the required distance by the forward movement of the carriage, thereby dispensing with one hand and avoid the annoyance and expense of mistakes. Each end of the log is set up at the same time, and no time is lost, as each time the carriage moves forward the log is set up the required distance before reaching the saw. The device is cheap and simple

in its construction, is easily operated by one man, and is not likely to get out of order.

Having thus fully described our invention, what we claim as new, and desire to secure by Letters Patent of the United States, is—

1. In a saw-mill carriage, the combination, with the carriage-frame provided with head-block guides, and head-block provided with rack-arms adapted to work in said guides, of a shaft having pinions engaging the head-block, 75 racks geared to a cross-shaft having a ratchet-wheel near one end, a loop-arm provided with a triple pawl engaging the ratchet-wheel, and a pivoted pawl adapted to engage a rack-bar on the track-frame, whereby the head-blocks 80 may be operated automatically by the forward motion of the carriage-frame, to set the log forward any predetermined distance, substantially as specified.

2. In a saw-mill carriage, the combination, 85 with the graduated rule provided with a knee-set adjustably secured thereon, secured to the saw-cab, of a carriage-frame provided with head-blocks, having rack-arms working in head-block guides, and mechanism for automatically feeding the head-blocks forward by 90 means of a set-pawl and rack-bar, when the carriage-frame is moved forward, substantially as specified.

3. In a saw-mill carriage, the combination 95 of the ratchet-wheel on the cross-shaft k , provided with gearing for operating the head-blocks in their guides, with the triple pawl m , face-plates, with loop l' , connected to the pivoted pawl o by an arm, the hinged detent, the 100 double-crank lever, and hook-rod connected thereto, and the rack-bar for engaging the hinged pawl o , substantially as specified.

4. In a saw-mill carriage, the combination, 105 with the longitudinal shaft having a miter-gear, and pinions engaging the rack-arms of the head-block, of the cross-shaft having a miter-gear and a ratchet-wheel and a ratchet-lever at the front end of the cross-shaft k , the triple lever and hinged detent, and mechanism for throwing the same out of gear, whereby the head-blocks may be moved to their starting-points by operating said ratchet-lever, 110 substantially as specified.

5. In a saw-mill carriage, the combination, 115 with the ratchet-wheel on the cross-shaft k , the curved rack and lever on said shaft, provided with the spring-pawl, the triple pawl, the pawl o , and pivoted detent, of the double crank and angular rod connected to its arm, 120 and the rack-bar working in guide-boxes on the track-frame, substantially as specified.

In testimony that we claim the foregoing as our own we have hereto affixed our signatures in presence of two witnesses.

VAN BUREN MARTIN.
CHARLES W. METCALFE.
